UNITED STATES PATENT OFFICE

GEORGE H. GARDNER, OF CHICAGO, ILLINOIS, ASSIGNOR TO THE MENASHA PRODUCTS COMPANY, OF CHICAGO, ILLINOIS, A CORPORATION OF WISCONSIN

CUTTER PACKAGE

Application filed October 21, 1929. Serial No. 401,309.

This invention relates to a cutter package and particularly to one for use with rolled material, such as paper and the like for dispensing the same in such manner as pieces 5 of desired length may be torn off against the cutter.

The package of this invention is especially useful for waxed and like paper utilized for wrapping food and the like and is arranged to 10 enclose such paper to protect the same from dust, and to allow ready withdrawal of the paper web in order that pieces of requisite sizes may be torn off as desired.

The invention further contemplates a package 15 made from a single blank of material, which is scored and folded to provide a package of the requisite form and arrangement.

An object of the invention is to provide a package for roll paper, whereby portions of 20 the paper may be withdrawn and torn off in desired lengths.

Another object of the invention is to provide a package which is economical to manufacture, easy to assemble, and efficient in use.

25 A further object of the invention is to provide a package for roll paper which may be utilized for shipping the paper as well as a receptacle for the same in use whereby portions of the paper may be withdrawn and torn off as desired.

A still further object of the invention is to provide a package for roll paper which is made from a blank scored and folded in such manner as to provide a proper package with 35 minimum of weight and one which may be easily and readily assembled into box-like form, in such manner as to be readily disassembled, if desired.

The above, other and further objects of the 40 invention will be apparent from the following description, accompanying drawings and appended claims.

According to the invention, a blank of material is scored and folded to provide a front, 45 bottom, rear, and top wall, as well as a second or supplemental front wall, the latter having end pieces with tuck in flaps for securing the several parts in box-like form. The two front walls provide a space or passageway through 50 which the web of the material within the

package may be withdrawn, and furthermore, a cutting blade is provided adjacent the passageway for tearing off strips of material as desired.

Embodiments of the invention are illustrated 55 in the accompanying drawings and the views thereof are as follows:

Figure 1 is a perspective view of a box embodying the present invention.

Figure 2 is a perspective view of the box of 60 Figure 1 with the second or supplemental front wall in opened position and showing details of construction.

Figure 3 is a view similar to Figure 2, showing a modified form of front wall having a 65 skirt which serves as a guideway for the paper.

Figure 4 is a view similar to Figure 2, showing another modified form of guideway integral with the front wall. 70

Figure 5 is a fragmental perspective view of one end of the box assembled except for the insertion of the tuck in tabs on the second or supplemental front wall.

Figure 6 is a fragmental perspective end 75 view of a box showing the parts in assembled relation.

Figure 7 is a plan view of the blank from which the box of Figure 2 is made.

Figure 8 is a fragmental portion of a blank 80 utilized in making the box of the form in Figure 3.

Figure 9 is a similar fragmental portion of a blank utilized in making the box of the form of Figure 4. 85

Figure 10 is a transverse vertical section through a box of the form of Figure 2.

Figure 11 is a similar sectional view through a box of the form of Figure 3.

Figure 12 is a vertical section through a box 90 of the form of Figure 4.

Portions of the blank and also certain parts of the box embodying this invention have been designated in particular terms; however, these terms are used merely for the sake 95 of convenience, and should not be construed as terms of limitation.

A box constructed in accordance with this invention is made from a single sheet of material blanked to provide a front wall, a top 100

wall, a rear wall, a bottom wall, and a second or supplemental front wall, certain of the walls having interlocking end pieces and the second or supplemental wall having end pieces 5 with tuck in flaps for tucking in against the rear wall to lock the parts into box-like form. The two front walls form a passageway from the interior of the box so that a web of material within the box may be readily withdrawn. Furthermore, the free margin of the second or supplemental front wall is provided with a tearing off blade which is preferably serrated to facilitate tearing off of the material within the box.

15 Figure 7 illustrates a blank from which the box illustrated in Figure 2 is made, and said blank includes five panels designated as follows:

Panel 1 is the second or supplemental front. 20 Panel 2 is the bottom. Panel 3 the rear wall. Panel 4 the top, and panel 5 the front wall or short side wall. The blank is scored to enable folding of the several panels into box-like form.

25 The height of the panel 5 is less than the opposite panel 3 to provide a withdrawal space for the web adjacent the front panels 1 and 5. Preferably, the height of the second front panel 1 is less than that of rear wall 3. 30 The panels 1 and 5 overlap to some extent to provide a passageway for the paper web.

The second or supplemental front panel 1 is provided with end pieces 6 which end pieces in turn have tuck in flaps 7 scored along the 35 lines 8, while the end pieces 6 are scored along the lines 9 and 10.

The panel 2 designated herein as the bottom panel is provided with end pieces 11 scored on the lines 9 and 10, and which end 40 pieces are provided with shaped notches 12 in the margins adjacent the end pieces 6 of panel 1 for interlocking with other end pieces of other panels, and also with inclined notches 13 in the end margins of the same.

45 Panel 3 designated herein as the rear wall has no end pieces of any character whatsoever, although it may be provided with end pieces if desirable.

Panel 4 designated as the top panel is provided with end pieces 14 having tongues 15 therein extending obliquely from the scored lines 9 and 10, with one side of the tongue longer than the other, which tongue is made by a long slit 16 extending from the scored 55 lines 9 and 10 beyond the free end of the tongue, and a short slit 17 joining the slit 16 near its outer end and terminating short of the lines 9 and 10.

The panel 5 designated herein as the front 60 panel is provided with end pieces 18 which are cut along lines 19 and 20 oblique and perpendicular, respectively, to the scored lines 9 and 10, thus making irregular shaped end pieces.

65 Figure 8 illustrates a fragmental portion of

a blank employed to make the box of the form shown in Figure 3, which blank is similar to that illustrated in Figure 7 except that the panel 5a has attached to it a plurality of 70 scored strips 21 and 22 which may be bent as indicated in Figures 3 and 11 to serve as a skirt or guideway for the web of the material within the package.

Figure 9 is a fragmental portion of a blank 75 employed to make the box of the form illustrated in Figure 4, and is similar in all respects to the blank in Figure 7 except that the front panel 5b in this instance is provided with a single scored portion 23, which may be bent as illustrated in Figures 4 and 80 12 to serve as a skirt or guideway for the web of the material within the package.

A box constructed in accordance with this invention when in closed position has the appearance of Figure 1.

85 Figure 2 illustrates a box embodying this invention made from the blank of Figure 7 with the second or supplemental front panel 1 opened and with the other panels arranged in box-like form by interlocking engagement 90 of certain end pieces on the same.

The blank of Figure 7 is assembled into box-like form as illustrated in Figures 1 and 2 of the drawings by bending the various panels along the score and interlocking the 95 end pieces 11 and 14 of the bottom and top panels 2 and 4 respectively, and then bringing the front panel 5 down in position as shown in Figure 2 and interlocking the end pieces 18 thereof with the interlocked end 100 pieces 11 and 14, as illustrated in Figure 2.

The portion 11a of an end piece 11 is inserted in the slit 16 of overlapping end piece 14 and the pointed end 11b is hooked over the tongue 15 of end piece 14, thus locking together end pieces 11 and 14. The box or package is fastened as to the top, bottom and rear panels or walls with the front panels 1 and 5 unfastened. A roll A of paper or like material is then inserted and the front panel or 110 wall 5 is locked in position by inserting the end pieces 18 between the outer surface of the exposed part of end piece 14 of panel 4 and the inner surface of the exposed part of end piece 11 of panel 2.

115 The web 24 of the roll A is pulled outwardly underneath the front wall 5 in the space provided, because of the shorter height of the wall 5.

The second or supplemental front wall 1 is 120 then folded against the wall 5 and the end pieces 6 folded against the interlocked end pieces 11, 14 and 18 and then the tuck in flaps 7 are inserted against the inner surface of the rear wall 3 thereby locking the package in box-like form.

125 It will be observed that the front panel 5 is shorter than the rear panel 3 and therefore provides a space as clearly illustrated in Figure 2 of the drawings. The web 24 is pro-

jected a sufficient distance to extend over the free edge of the second or supplemental wall 1 when the same is folded upwardly against the front panel 5 and interlocked in position 5 by tucking the flaps 7 against the inner surface of the rear wall 3, as illustrated in Figure 5. This arrangement provides a passageway between the front panel 5 and the second or supplemental panel 1 for withdrawal of 10 the web 24 of the material within the package or container.

Figure 3 shows a box embodying use of the two scored sections 21 and 22 formed as a part of the front panel 5 and which are bent 15 inwardly as illustrated in Figure 11, and also in Figure 2 to serve as a curved end for the passageway between the front panel 5 and the second or supplemental front panel 1; otherwise, the box is constructed in the 20 manner as heretofore described.

Figure 4 illustrates a box made with the single supplemental guide piece 23, as shown in Figure 9 and in use appears as shown in Figures 12 and 4.

25 The gist of the invention resides in the formation of a box from a single piece of material scored and folded to provide a front panel and a supplemental front panel, forming a passageway therebetween for withdrawal of the web of material within the container.

A tear off blade or cutting edge member 25 having preferably a serrated edge 26 is secured to the free edge of the second or supplemental front panel 1 and is arranged flush with the top edge of said front panel or a slight distance above the same, if desired but in any event below the surface of the top 4. The blade 25 aids in severing the desired 40 length of material from the web 24, after the web has been withdrawn a sufficient amount to provide a piece of the desired size.

Should it be found necessary to open the box to replace the exhausted roll of material, 45 then the end flaps 7 of the end pieces 6 of the second or supplemental front panel 1 are withdrawn and the panel opened as shown in Figure 2, and then the end pieces 18 of the front panel 5 are unlocked, the panel then 50 raised and a new roll of material inserted, whereupon the panel 5 is locked in position and the front or supplemental panel 1 replaced as heretofore described.

A package or box made in accordance with 55 this invention may, because of the construction of the same, be made of thin and relatively inexpensive material. The formation of the box and the interlocking of certain end pieces provides a structure which is sufficiently rigid for the purpose intended, and one which may be used for a considerable period of time. A box embodying this invention is such as to readily enable the tearing off of desired lengths of material from 60 the roll contained in the same with clean lines

of severage as such tearing is done against the tear off strip 25 which may be a metal strip or of other material as desired.

A hole 27 is cut in the top and front walls 4 and 5 to enable grasping the free end of the web 24 of the paper for withdrawing the same. A flap 28 is formed in one of the other walls, here shown in the rear wall 3, whereby a thumb may be inserted to hold the roll A while tearing off a portion of the web 24.

75 The invention has been described herein more or less precisely, yet it is to be understood that the invention is not to be limited thereby, as changes may be made in the arrangement and proportion of parts and equivalents may be substituted without departing from the spirit and scope of the invention.

76 The invention is claimed as follows:

1. A foldable box blank made from a single piece of material foldable to provide a closed box having front and rear walls, a top, a bottom, and a second or supplemental front wall overlying said first mentioned front wall, said top, bottom, and first mentioned front wall having interlocking end pieces, said second mentioned front wall having end pieces with tuck in flaps thereon arranged so that when the blank is assembled into box-like form the end pieces of said second mentioned front wall overlie and cover the interlocking end pieces of the other portions with the flaps tucked in against the rear wall to lock said parts in position, said first and second front walls providing a passageway, a roll of material within said box having its free end in said passageway for withdrawal therefrom, and a serrated blade attached to the free edge of said second mentioned front wall.

85 90 95 100 105 110 115 120 125

2. A carton in the form of an elongated box made from a single blank scored and folded into box-form having top, bottom, front and back sides which may be readily assembled and disassembled; said top having a downwardly projecting portion constituting a short side wall and terminating short of the bottom; said top and said short side wall having end tabs which are interlocked together; said bottom having end tabs which are interlocked with the end tabs of said top and said short side wall; said front being foldable against said short side wall to provide with it a withdrawal guideway for the box contents; said front being of less height than the box and having its free edge terminating below the box top; a tear-off strip secured along the free edge of said front and with its tear-off edge lying below the box top; said front having end tabs and tuck-in flaps thereon; said tuck-in flaps being inserted between the interlocked ends of said top, short side wall and bottom and against the back for maintaining said front in position; said front being swingable away from said short side

wall when said tuck-in flaps are freed to allow unlocking of said interlocked end tabs and opening said box for replenishment of its contents.

5 In testimony whereof I have hereunto subscribed my name at Chicago, Cook County, Illinois.

GEORGE H. GARDNER.
